UNITED STATES PATENT OFFICE

2,005,006

DRIVE MECHANISM FOR MECHANICAL STOKERS

Herbert E. Preston, Philadelphia, Pa., assignor to American Engineering Company, Philadelphia, Pa., a corporation of Pennsylvania

Application June 5, 1931, Serial No. 542,383

5 Claims. (Cl. 110—44)

This invention relates to improvements in mechanical stokers, and relates more particularly to improvements in the means for operating the fuel-feeding parts of a multiple retort underfeed

5 stoker of the general character disclosed in U. S. Patent No. 1,443,202.

While the rams and pushers of a stoker of the stated type have previously been operated by hydraulic mechanism, these prior hydraulic drives 10 have been relatively inflexible as regards relative or individual adjustments of the individual rams and pushers, and it is an object of the present invention to provide an hydraulic drive having provision for independent and relative adjustments of the various driven parts.

15 The invention further resides in certain novel structural details hereinafter set forth and illustrated in the attached drawings, in which:

Figure 1 is a side elevational view partly in 20 section with the pumping apparatus removed illustrating a stoker drive made in accordance with my invention;

Fig. 2 is a vertical sectional view of the mechanism;

25 Fig. 3 is a section on the line 3—3, Fig. 2;

Fig. 4 is a fragmentary sectional view showing details of the pusher-actuating rods and their supporting means;

Fig. 5 is a fragmentary plan view illustrating 30 a detail of the rod connections, and

Fig. 6 is a section on the line 6—6, Fig. 4;

Fig. 7 is a partial plan view of the stoker structure showing a plurality of the retorts and the mechanism associated therewith.

35 With reference to the drawings, 1 is the front wall of a furnace equipped with a stoker made in accordance with my invention, and 2 is a ram housing secured against the outer face of the wall and provided at the top with a port 3 which com-

40 municates with the bottom of a fuel hopper 4. Mounted for reciprocation within the housing 2 is a ram 5 which in an advanced position as shown in the drawings effectively closes the port 3, said ram when retracted permitting a gravity

45 flow of fuel from the hopper 4 into the housing 2, which fuel is projected by the ram in its next advance movement through a port 6 in the front wall 1 onto a dead plate 7 which constitutes the upper bottom portion of one of a series of retorts

50 which with intermediate tuyères constitutes the fuel-supporting section of the stoker wherein combustion of the fuel occurs. Each of the retorts is provided with a series of reciprocatory pushers 8 which constitute the bottom walls of

55 the retorts, or a part thereof, and which by re-

ciprocating effect a progressive movement of the fuel over the fuel-supporting section of the stoker. In the present instance, one only of the secondary or retort pushers 8 is illustrated.

As shown in Fig. 2, the ram 5, which as will be apparent from the above description constitutes one of a series of rams associated individually with the respective retorts of the stoker, is hollow and is open at its front end for reception of a piston 11. The front end of the hollow ram 10 is closed by means of a head 12 which has an opening for passage therethrough of a rod 13, to the rear end of which the said piston 11 is secured. In the present instance, the piston 11 is threaded for reception of a correspondingly threaded end of a rod 13. The joint between the head 12 and the cylinder body is sealed by means of a suitable gasket, and suitable packing means is provided between the rod 13 and the head 12 to prevent leakage from the interior of 20 the ram. The rod 13 is rigidly secured at its outer end in a bracket 14 secured at its upper end directly to the housing 2, and at its forward and lower end to the outer end of an extension bracket 15 attached to the lower forward portion of the housing 2.

The rod 13, as illustrated in Fig. 3, is provided with two longitudinal passages 16 and 17, respectively, these passages communicating at the forward or outer end of the rod, which as previously 30 stated is fixed in the bracket 14, with a pair of ducts 18 and 19 respectively, which connect to suitable fluid-pumping apparatus designated generally by the reference numeral 21, see Fig. 2, which in the present instance is mounted at the 35 top of the bracket 14. The inner end of the passage 16 is closed in the present instance by means of a plug 22 threaded into the end of the rod 13, and this channel also has one or more ports 23 which communicate with a countersunk recess 24 40 at the outer end of the piston 11. This port 23 provides for application of fluid pressure between the piston 11 and the head 12 of the ram. The inner end of the passage 17 communicates directly with the chamber at the inner end of the 45 piston 11 and provides for application of fluid pressure between the piston and the inner end of the hollow ram. Preferably, the hollow ram, the passages 16 and 17 and the ducts 18 and 19 form with the pumping apparatus 21 a closed fluid circuit, and in operation the pump or pumps 21 operate simultaneously to evacuate the ram chamber at one side of the piston 11 and to apply pressure to the other side whereby the hollow ram is caused to reciprocate within the housing 2 in the 50 55

performance of the fuel-feeding function described above. The pumping apparatus 21 may take the form of a reversible discharge pump which functions alternately to apply pressure and 5 to evacuate the interior chambers of the ram 5 at opposite sides of the piston to effect the aforesaid reciprocatory movement of the ram.

The bracket extension 15 forms a journal for a rock shaft 25, to the opposite ends of which are 10 secured levers 26. The upper ends of these levers are secured through the medium of links 27 to opposite sides of the ram head 12, while between the lower ends of the said levers are pivotally mounted in the present instance a pair of blocks 15 28 and 29, each of which blocks is apertured for reception of one or more rods 31 and 32, respectively, and these rods 31 and 32 are connected through suitable couplings 33 to rods 34 and 35 which extend through the lower portion of the 20 front wall 1 of the furnace and constitute the means for actuating the secondary fuel-feeding rams or pushers 8, a series of which as previously described are mounted in the bottoms of the stoker retorts.

Referring to Fig. 4, it will be noted that the front wall 1 is provided with an opening in which are secured brackets 51 and 52 through which the rods 34 and 35 respectively extend and which are formed to support and guide said rods. 25 Each of the brackets is provided at its outer end with a recess 53 for reception of a suitable packing and a follower gland 54, which latter is held in position by means of studs 55 secured in the end of the bracket and extending through the 30 flange of the said gland. An efficient stuffing box is thus formed which effectively prevents leakage of air or dust from the interior of the wall. At the inner end, each of the brackets is formed with an extension 56, the inner end of 35 which terminates in a bearing 57 for the respective rods. In that part which passes through the bearing, each of the rods is formed with a flat portion 58, see Fig. 6, which engages a segmental piece 59 secured in the associated bearing 57 by 40 bolts 61. The arrangement affords a sliding fit for the rods in the bearings while preventing any angular or turning movement of the rods. The brackets 51 and 52 thus function not only to afford an extended supporting guide for the rods, 45 but provide for sealing the joint where the said rods pass through the wall 1 and also incorporate means for preventing rotation of the rods from a normal position. The rods 34 and 35 are individually secured to the rods 41 by means of pins 50 62, see Figs. 4 and 5, these pins being maintained in position in the bifurcated inner ends of the rods 34 and 35 by means of a wedge or equivalent element 63 inserted in an aperture 64 in the said 55 ends of the rods, this element engaging in a circumferential recess 65 in the pin 62, as shown in Fig. 4, and thereby preventing any axial movement of the pin in the supporting member. The pins 62, however, may be readily withdrawn by 60 first removing the element 63. The pins 62 may be adapted to fracture under a predetermined strain to thereby constitute a safety element in the transmission line between the prime mover and the pushers. Frangible pins 66 may also be employed to secure the collars 45 and 46 to the rods 31 and 32.

Fig. 1 illustrates the method of connecting the rod 34 to the pusher 8, this connection consisting of a lever 36 pivotally secured to a retort dead plate 37, which lever is connected through 75 a suitable link 38 to the pusher 8, and through a

link 39 to the rod 34. Similar means may be employed for connecting the said rods to the other pushers of the retort, and preferably and as illustrated in Fig. 1, the rods 34 and 35 are provided with branches designated generally by the reference numeral 41 which provide independent connections for the individual fuel-feeding elements. These separate connections may be adjustable if desired to permit individual adjustments of the secondary pushers with respect to the main actuating rods 34 and 35.

Means is also provided illustrated in Fig. 2 for adjusting these rods 34 and 35 with respect to the common operating lever 26. Each of the rods 31 and 32 is provided with a collar 45 adapted to abut the inner sides of the blocks 28, and the outer ends of the rods are also provided with terminal collars 46. Intermediate the collars 45, the rods are adapted for reception of one or more horseshoe washers 47, the number and location of which determine the operative relation between the rods 31 and 32 and their respective blocks. It will be noted that the primary ram 5 constitutes in itself the main actuating member for the fuel-feeding elements, and that by interposing the lever 26 between the ram 5 and the operating rods of the secondary rams, a highly flexible connection is established affording a desired adjustment between the individual fuel-feeding elements.

It will be apparent that the invention is not limited to the particular adjustment means herein described and illustrated, and that there may be considerable modification in detail without departing from the spirit of the invention as defined in the appended claims. The invention is particularly valuable in connection with multiple retort underfeed stokers of the type mentioned above having retorts of considerable length wherein difficulty is experienced in maintaining a proper disposition of fuel over the extended combustion area.

I claim:

1. A mechanical stoker comprising a retort, a cylinder associated with said retort, a ram operating in said cylinder for feeding fuel to said retort, said ram projecting at one end from said cylinder, a plurality of fuel feeding pushers located in the bottom of said retort, hydraulic mechanism for actuating the ram, a plurality of rods, and fixed guides therefor supporting the rods for longitudinal reciprocation, links connecting said rods individually with said pushers, a lever operatively connected to the projecting end of said ram at a point substantially midway between the top and bottom thereof and adapted for oscillation by reciprocation of the latter, and adjustable means for operatively connecting said lever with the rods, said adjustment providing for relative variation of the movements of said pushers.

2. A mechanical stoker comprising a retort, a cylinder associated with said retort, a ram operating in said cylinder for feeding fuel to said retort, said ram projecting at one end from said cylinder, a plurality of fuel feeding pushers located in the bottom of said retort, an actuating rod for each of said pushers, and means for supporting said rods for longitudinal reciprocation, means operatively connecting the rods with the individual pushers, hydraulic mechanism for actuating the ram, a lever having a fixed pivot and operatively connected to the projecting end of said ram at a point substantially midway between the top and bottom thereof, blocks pivotally

mounted on said lever, and rods adjustable longitudinally in said blocks and pivotally connected with said first-named rods whereby actuation of the ram results in a predetermined actuation of said pushers.

5. A mechanical stoker comprising a retort, a cylinder associated with said retort, a ram operating in said cylinder for feeding fuel to said retort, said ram projecting at one end from said cylinder, a plurality of fuel feeding pushers located in the bottom of said retort, hydraulic mechanism for actuating the ram, actuating rods for the individual pushers, means for operatively connecting said rods with the pushers, and means including a lever operatively connected to the projecting end of said ram at a point substantially midway between the top and bottom thereof for longitudinally reciprocating said rods in predetermined fixed paths in timed relation with the movement of said ram.
10. 3. A mechanical stoker comprising a retort, a cylinder associated with said retort, a ram operating in said cylinder for feeding fuel to said retort, said ram projecting at one end from said cylinder, a plurality of fuel feeding pushers located in the bottom of said retort, hydraulic mechanism for actuating the ram, actuating rods for the individual pushers, means for operatively connecting said rods with the pushers, and means including a lever operatively connected to the projecting end of said ram at a point substantially midway between the top and bottom thereof for longitudinally reciprocating said rods in predetermined fixed paths in timed relation with the movement of said ram.
15. 4. In a mechanical stoker, the combination with a front wall of a furnace, of a fuel-supporting section extending inwardly from said wall and comprising alternately arranged retorts and tuyères, openings in said wall providing access to the upper ends of the retorts, working cylinders secured to said front wall and communicating with said openings, a fuel hopper associated with each of said cylinders, a ram adapted for reciprocation in each of said cylinders to feed fuel from said hopper into the retorts, one end of each of said rams projecting from the corresponding cylinder hydraulic mechanism for actu-

ating said rams, a lever mechanism connected to the projecting end of each of said rams and mounted for oscillation by reciprocation of the latter, a plurality of fuel feeding pushers in each of said retorts, an actuating rod for each of said pushers, fixed guides in said front wall for said rods wherein the rods are confined for longitudinal reciprocation, means for operatively connecting said rods with the respective pushers, and means for flexibly and adjustably connecting said rods with the said lever mechanism whereby actuation of the ram results in a synchronized actuation of said pushers.

5. A mechanical stoker comprising a fuel supporting section, including alternately arranged retorts and tuyères, a cylinder associated with each of said retorts, a plurality of rams, one of said rams operating in each of said cylinders for feeding fuel to said retorts, one end of each of said rams projecting from the corresponding cylinder, a plurality of fuel feeding pushers located at the bottom of each of said retorts, a plurality of rods respectively operatively connected with said pushers, means for guiding said rods for longitudinal reciprocation, hydraulic mechanism for actuating said rams, a pair of levers connected to the projecting end of each of said rams at opposite sides of the longitudinal center line thereof, and links flexibly connecting said rods with said levers whereby actuation of the ram through the medium of the hydraulic mechanism results in an actuation of said pushers.

HERBERT E. PRESTON.
